(57) **CLAIM**

The ornamental design for a screw cap with tabs, as shown and described.

DESCRIPTION

FIG. 1 is a perspective view of the screw cap with tabs of my new design;

FIG. 2 is a top view of the screw cap with tabs of my new design;

FIG. 3 is a front view of the screw cap with tabs of my new design, with a back view being identical to the front view; and,

FIG. 4 is a bottom perspective view of the screw cap with tabs of my new design.

The broken lines depict portions of the screw cap with tabs that form no part of the claimed design.
